UNITED STATES PATENT OFFICE.

GEORGE C. PYLE, OF WILMINGTON, DELAWARE, ASSIGNOR TO DANIEL H. KENT, OF SAME PLACE.

HORSESHOE-MACHINE.

SPECIFICATION forming part of Letters Patent No. 234,200, dated November 9, 1880.

Application filed October 2, 1879.

To all whom it may concern:

Be it known that I, GEORGE C. PYLE, of the city of Wilmington, county of New Castle, State of Delaware, have invented certain new and useful Improvements in Horseshoe-Machines, of which the following is a specification.

In the accompanying drawings, Figure 1 is a plan, and Fig. 2 a side elevation, of my invention. Fig. 3 is a vertical longitudinal section upon the line $x-x$ of Fig. 1. Fig. 4 is a plan of the machine upon the level of the shoe-formers, the parts above being removed. Fig. 5 is an end view, and Fig. 6 a cross-section upon the line $y-y$ of Figs. 1 and 2. Fig. 7 is a detail section of the hammer. Fig. 7^x is an elevation of the feed-rollers viewed in the direction of the feed. Fig. 8 is an elevation of the same viewed in a direction perpendicular to the line of feed. Fig. 9 is an elevation showing the stop which holds the hammer-frame down while the hammer is in action. Fig. 10 is a vertical transverse section on the line of the main shaft.

Corresponding letters indicate corresponding parts wherever used.

In the drawings, A represents a suitable frame-work, of metal, of a machine embodying duplicate sets of shoe-forming mechanisms, either of which may be used separately when desired. Of course, if a machine were originally made with but one set of these mechanisms, some details of the devices which operate them would need change; but such changes are possible to any skilled mechanic without invention.

In my description of parts, which are duplicated at each end of the machine, I shall confine the description to one of them.

Power is communicated to the machine through the pulley A' upon the shaft A², which also bears a fly-wheel, A³.

The bar from which the shoes are formed is fed to the operating devices by a spring-depressed feed-roll, B, one end whereof is a bevel-gear meshing into another gear, B', upon a shaft, B², operated through a universal joint, b, by gears B³, B⁴, and B⁵, the latter being upon the shaft A². The roll B revolves upon

the rounded end of a piece, B⁶, resting in a pivoted arm, b', and in another top recess in the arm b², projecting out from the frame-work, it thus being free to rise and accommodate the thickness of the incoming metal, which rides upon the anti-friction roller or rollers b³.

The spring B⁷ depresses the part B⁶ and the roll at all times. The shaft B² has its upper bearing in the part B⁶, and the shaft B⁸, to which it is connected by the universal joint, carries the gear B³, before mentioned. This gear, however, is loose upon said shaft, and is provided with recesses upon its side, which are clutched, when desired, by the points B⁹, projecting outward from the shaft, the wheel being shifted by an elbow-lever, B¹⁰, attached to the frame-work, a connecting-rod, B¹¹, and a Y-shaped piece, B¹², setting down upon the sleeve of the gear. This clutch is intended to be used only when it is desired to start or stop the feed, which is done by the attendant through the medium of the elbow-lever. The rotation of the feed-roll B is, under ordinary circumstances, continuous, but may be stopped very readily and quickly in the way described.

When the forward end of the bar has reached the gage C a blank for a single shoe is cut off by the knife C', borne upon a shaft, C², and partially rotated downward with a positive force sufficient to insure the work of the knife by a cam, b⁴, upon the wheel B⁴, and a lever, C³, secured to the shaft C², with which lever said cam comes in contact at each revolution. When the blank has been severed the knife remains opposite the opening i, through which the bar issues from the feed-roll, and prevents all further feed of material until the bending parts have returned and are ready to receive another blank, when it is thrown up and back to its first position by the spring C⁴, secured to the lever C³ and to the mate of said lever at the other end of the machine or to a fixed point.

In point of time this severing takes place while the bending-jaws and former or shaping-block—presently to be described—are in the position shown at the right of Fig. 4. The severed blank falls with its ends resting upon reciprocating slides D, and behind a bar, D',

secured at either end to said slides by pins d , upon which it is at liberty to rise and fall, and in front of the jaws and former. The blank is then carried by the backward reciprocation of the slides and the bar, the jaws also retreating at the same time and the former sinking below the plane of the blank, so as to offer no obstruction until the parts have reached the position shown in Fig. 4, at the left. The blank 15 may be held against longitudinal play during this movement by stops d' upon the slides, if necessary. The blank now rests with its center over the annular anvil D^2 , surrounding the shaping-block, and is ready for bending. Before the bending commences the said former D^3 rises from its sunken position, raising with it the bar D' , and detaining the latter in the elevated position until the completion of the forward movement, which is next in order. 20 The bending-jaws D^4 are now forced forward simultaneously, and each seizing an end of the blank, bend it around the forming-block D^3 , completing this portion of their office when they have reached the position from which 25 they started—viz., that shown at the right of Fig. 4. The said forming-block extends downward through the portion of the frame in which it is held, and is intermittently raised and lowered at proper times by the cam D^5 upon the shaft D^6 , bearing the said wheel B^4 , such cam being continued sufficiently to sustain the former during the length of time it is required to be held in the raised position, and when that period is over it drops by its own gravity. The 30 bent wire D^7 , depending from the former, is for the purpose of freeing the former with certainty from the embrace of the formed shoe, which it is caused to do by the contact with it of the pin d upon the side of the cam D^5 . 35 This device, or some other accomplishing the same result, I find to be essential, as gravity is not always sufficient for the purpose.

The bending-jaws D^4 are pivoted at their rear ends in a sliding head, D^8 , and at their 40 forward ends are connected to the stationary frame-work by tie-rods or bars D^9 ; but they come in contact in their forward reciprocation each with a rotating cam, D^{10} , and are by such cams forced to their work of bending the blank 45 around the shaping-block D^3 . Said cams are mounted upon vertical shafts D^{11} , receiving motion through the gears D^{12} and D^{13} from the shaft D^6 . The rounded portions of the cams produce a dwell by the jaws in the positions 50 they occupy while compressing the bent blank around the shaping-block sufficiently long to permit the metal to set in its new shape and to allow the hammer to operate thereon, as hereinafter specified.

The head D^8 is impelled forward by one or 55 more swinging levers, D^{14} , secured at the free end to the head, and at the bottom pivoted to the frame and operated intermittently by rotating eccentrics D^{15} , mounted upon the shaft D^6 , and motived by the large gear D^{17} and the gear B^5 , already mentioned.

The eccentrics D^{15} may be made of horizontal bars held in suitable frame-work, D^{19} , secured to the said shaft D^6 . The conformation of the arms D^{14} should be such that they continue to receive force from the eccentrics during the period of the dwell, before stated, of the bending-jaws. As soon as the eccentrics pass beyond contact the springs D^{20} , secured at either end to the heads D^8 , (or, in case of a single machine, secured at one end to a stationary point,) pull the head and the parts connected therewith back to the position shown at the left of Fig. 4—viz., the position occupied by them previous to the commencement of the bending operation. The slides D are also connected to the head D^8 by tie-connections D^{21} . The bending being now complete and the blank being closely confined in the recess formed between the bending-jaws and the forming-block above the annular anvil, I subject the blank to a forging operation designed to finish the shaping, to impart the desired impress to the flat sides of the shoe, and to compact and densify the material. This I do by means of the hammer E . This hammer reciprocates in a vertical opening through a rigid part, A^3 , of the frame, and is guided by guide-ways at the front and rear of said opening, 85 corresponding with the projections e upon the hammer, which occupy said ways. Centrally through the hammer passes a rod, E^1 , cushioned above and below by springs e' , and with its ends inserted in pitmen E^2 , connected with cranks in the shaft E^3 , which is actuated from the gear E^4 and the large gear D^{17} , which communicate such motion, by pulleys E^5 and E^6 and their connecting-belts, to the hammer-shaft. 90

The impact of the hammer is caused to be intermittent, although its motion is continuous, by the raising at proper intervals of the frame E^1 , which supports its shaft. This is done by levers E^9 , pivoted at e^9 , which are raised by cams E^{10} upon the shaft D^6 , said levers, in their turn, raising said frame E^1 sufficiently to take the hammer out of reach during the feeding in and bending of the blank. 105

To steady the hammer during the forging, 110 and to prevent unnecessary upward rebound, I lock the frame E^1 down while that operation is in progress by catch-levers E^{11} upon said frame and pins E^{12} upon the stationary or main frame of the machine. These catches 115 are automatically thrown into and out of engagement with the pins at the proper times by a pin, E^{13} , upon the wheel B^4 , which, at every revolution of said wheel, strikes a lever, E^{24} , keyed upon a shaft, E^{15} , causing said shaft to 120 move through a partial revolution, and thereby to vibrate the cranks E^{16} upon said shaft, and thereby, through the connecting-pieces E^{17} , to move the catch-levers. Of course, the hammer is provided with a die, E^{18} , hollow interiorly, so as to allow it to set down over the 125 shaping-block. 130

In order that the hammer and anvil may not come in contact at times when no material is being fed into the machine, I have provided an automatic arrangement preventing such contact and the consequent injury to the parts which would be caused thereby. This arrangement consists of a trip, G, pivoted to the main frame at g, and provided with a lateral arm, g', extending to the under side of the shaft of the feed-roll B, and compelled to press up against said shaft by a counter-balance, g², applied to the opposite side of the trip. It results from this construction that whenever the material ceases to be fed to the feed-roll and said roll drops in obedience to its spring, the shaft of the feed-roll tilts the trip, so that when the hammer-frame descends it will rest upon the trip in the manner shown in Fig. 5. When the feeding is resumed the trip will be automatically tilted back by its counter-balance.

The completed shoe is thrust out of the machine by the new blank and the bar D' when they move back, and it falls upon a chute, H, which conducts it to the front of the machine. The boxes of the cam-shafts D¹¹ are made movable within certain limits to permit the taking up of the wear. They are provided with flanges o, which rest upon shoulders o', and are held firmly by a set-screw, o², and wedges o³ and screw o⁴. When they need adjusting one of the wedges is moved by the screw o⁴, and after adjustment the screw o² may be tightened upon the box.

In the duplicate machine shown in the drawings, it will be noticed that the operations of the two sets of mechanisms alternate with each other—that is to say, while the blank is being bent by one set another blank is being forged by the other set. This I am enabled to do by placing the eccentrics or cams which operate the heads carrying the bending-jaws upon the same shaft and by properly timing them thereon.

The hammer-shaft is so timed that it causes the hammer to give several blows to the shoe while it is imprisoned by the forming mechanisms. This insures perfect results, because the shoe is unable to spread at the sides, and must therefore be much solidified and made to conform very perfectly to the dies upon the hammer and anvil, giving it thus a fine and smooth finish.

The eccentrics upon the shaft D¹⁶ are of peculiar construction, and are adjustable with great nicety. They consist of bars D¹⁵, laid horizontal and parallel to the shaft, and are held between set-screws m m, setting against the same from opposite directions, there being two at each end of the bar.

What I claim, and desire to secure by Letters Patent, is—

1. In a machine for making horseshoes, the combination, with mechanism for bending the blank, of a continuously-running hammer, E, the crank-shaft E³, and swinging frame E⁴, which is pivoted coincident with the axis of

the driving-shaft E⁶, and mechanism for operating said frame, whereby said hammer may be raised out of action without ceasing its reciprocation.

2. The hammer E, hammer-frame E¹⁴, bending mechanism, feed mechanism, and anvil, all substantially as described, combined with a trip, G, controlled by said feed mechanism, and thereby caused to arrest the hammer-frame whenever said feed mechanism is not acting upon material.

3. The frame E¹⁴, whereon the hammer and its driving crank-shaft are mounted, combined with the lever E⁹, which moves upon a point behind and below the shaft E⁶ and bears upon said frame at a point in front of said shaft, and the cam E¹⁰ near to the extremity of said lever, whereby said frame is periodically raised and lowered, as set forth.

4. A forging mechanism consisting of a frame, E¹⁴, pivoted at the extremity of its side arms to the main frame around the shaft E⁶, mechanism for operating said frame, and a hammer suspended in said frame by a rotating crank, E³, combined with driving-pulleys upon said shaft E⁶, and connecting-belts, whereby said hammer may be raised so that it will not deliver its blow, but without pausing in its reciprocation.

5. The pivoted frame E¹⁴, within which the hammer and its driving-shaft are mounted, combined with the feeding-rollers, the upper one whereof may move up and down to conform to the thickness of the material to be fed, and the bell-crank arm G, pivoted to the main frame of the machine, and controlled by said movable feed-roller, and provided with the counterbalance-weight g², whereby, when no material is between the feed-rollers, said arm G will be caused to arrest the frame E¹⁴, and when the feed is in action it will be thrown back out of engagement therewith.

6. In a horseshoe-machine, the combination of feeding mechanism feeding the blank in front of the forming mechanisms, the forming mechanisms having a shaping-block which sinks when the shoe is finished, and a push-bar carried by reciprocating mechanism, and operating to discharge the finished shoe and to move the next blank into position by a single movement, substantially as specified.

7. The combination, with the bending mechanism having a shaping-block which sinks when the shoe is to be discharged, of a reciprocating pushing-bar for positioning the severed blank with reference to the bending mechanism, and which bar is caused to rise out of the way when that mechanism is operating, substantially as specified.

8. In combination with an intermittently-striking hammer, the latch E¹¹ and stop E¹², for locking the frame supporting the hammer against rebounding while the hammer is striking, substantially as specified.

9. The eccentrics upon the shaft D¹⁶, constructed of longitudinal bars mounted in a

frame-work secured upon the shaft and adjustable in such frame-work, substantially as specified.

10. The feed-roll B, mounted on the end of the bar B⁶, which is movable in a vertical plane, and depressed by the spring B⁵, combined with the driving-gear B' upon the shaft B², which also has its bearing in the bar B⁶, and the driving-pinion B³ and flexible connection b, for the purpose stated.

11. The trip G, jointly with the mechanism for operating the same, whereby said trip is automatically brought into action to arrest and hold up the frame E whenever there is no material between the feed-rolls.

GEORGE C. PYLE.
